[57] CLAIM

The ornamental design for a spoke segment for an automotive vehicle wheel, as shown and described.

DESCRIPTION

FIG. 1 is a perspective view of a spoke segment for an automotive vehicle wheel, showing my new design; and, FIG. 2 is a front view thereof.

The broken lines adjacent to the spoke member in the center hub area define the bounds of the claimed design and form no part thereof while the remaining broken lines depict environment for illustrative purposes only and forms no part of the claimed design.
